UNITED STATES PATENT OFFICE.

GERALD H. SIMON, OF NEW YORK, N. Y., ASSIGNOR TO SIMON MILLINERY CO., OF SAN FRANCISCO, CALIFORNIA, A CORPORATION OF CALIFORNIA.

DESIGN FOR A LADY'S HAT.

Application filed July 21, 1927. Serial No. 22,827. Term of patent 3½ years.

To all whom it may concern:

Be it known that I, GERALD H. SIMON, a citizen of the United States, and a resident of the city of New York, borough of Manhattan, in the county and State of New York, have invented a new, original, and ornamental Design for Lady's Hat, of which the following is a specification, reference being had to the accompanying drawing, forming part thereof.

The drawing is a perspective view of a lady's hat showing my new design, the dotted lines indicating the head of a wearer.

I claim:

The ornamental design for a lady's hat, substantially as shown and described.

GERALD H. SIMON.
